UNITED STATES PATENT OFFICE.

ALFRED CROOK, OF PHILADELPHIA, PENNSYLVANIA, ASSIGNOR TO TAYLOR-WHARTON IRON AND STEEL COMPANY, OF HIGH BRIDGE, NEW JERSEY, A CORPORATION OF NEW JERSEY.

MEANS FOR CONTROLLING CONTINUOUS ROLLING MILLS.

Application filed November 25, 1919. Serial No. 340,512.

To all whom it may concern:

Be it known that I, ALFRED CROOK, a citizen of the United States, residing at Philadelphia, in the county of Philadelphia and 5 State of Pennsylvania, have invented certain new and useful Improvements in Means for Controlling Continuous Rolling Mills, of which the following is a specification.

This invention relates to an improvement 10 in mechanical controls of the type adapted to govern a plural machine drive involving variable speed gears.

In drives of this type, as for example, in a continuous rolling mill drive where the 15 mills are driven by independent fluid gears, each served by a variable-speed delivery pump, with all pumps operated by a common prime mover, the speed variation of the drive is obtained through controlling the 20 rate of pressure fluid from each pump, a single lever ordinarily serving for the control of each unit. It is important that the drive be controlled, not only as an entirety, but that the speed ratio of each independent 25 unit be separately controlled.

The present invention, therefore, is particularly directed to a control through which the speed ratio of each independent unit 30 may be controlled, or the speed ratio of all units simultaneously and similarly governed, while maintaining the independent relative ratios of the respective units. This permits the operation of each unit at desired speed, in order that such unit may perform the desired work, while at the same time affording 35 a simultaneous and relative proportional control for all units, necessary, for example, in load changes.

In the drawings:

40 Fig. 1 is a plan, illustrating the application of the improvement to a rolling mill drive.

Fig. 2 is an end elevation partly broken out of Fig. 1.

45 Fig. 3 is an enlarged view of the speed adjuster.

Fig. 4 is a longitudinal section of the same.

Fig. 5 is an elevation of the adjuster set for the minimum or zero speed. 50

Fig. 6 is a view in elevation, showing a modified adaptation of the speed adjuster.

The invention is here shown as applied to a continuous rolling mill, and while particularly effective in such application, is equally 55 applicable to other drives, as will be apparent.

In the illustration given, rolling stands 1, are driven by variable speed hydraulic motors 2, through the pinion pair 3, by means 60 of the crank 4. The top roll 5 is adjustable by the usual screw-down 6, and the center differences of the rolls and pinions are taken care of by wobblers 7.

The motors 2 are each served by a variable 65 speed delivery pump, and all pumps are operated at constant and uniform speed by a prime mover 8. Each pump is provided with a delivery-change control lever 9, and through the operation of these levers the rate 70 of flow of pressure fluid from the particular pump to the motor is controlled, to thereby govern the speed of the motor and of the load machine.

It is important that the speed variation of 75 each unit be capable of separate control, in order that the particular mill or other load machine may carry out its prescribed work, and it is also of prime importance that means be provided for simultaneously and similarly 80 controlling the speed variation of all units, as in load changes. The present invention, through the adjuster now to be described, provides a means for independently controlling each unit, while at the same time permitting the simultaneous control of all units. 85

The adjuster, which is shown more particularly in Figs. 3, 4, and 5, comprises a rectangular frame 10, pivotally supported at one end on brackets 11, fixed to an appropriate part of the system, as adjacent the prime mover. Threaded rods 12 are mounted in the frame for rotative movement, while held against independent longitudinal movement. The rods have crank handle ends 13, 90 beyond the frame, whereby any rod or rods

may be selectively rotated. The rods 12 are equal in number to the number of control levers 9, and such rods 12 are each provided with a traveling nut 14 having threaded co-

5 operation therewith. Each nut carries a block 15, mounted for free rotation relative to the nut, and the blocks 15 are each slidably mounted in elongated rectangular cross-heads 16. The cross-heads 16 form the fixed 10 terminals of rods 17, leading to the respective levers 9, so that each lever 9 has an independent sliding connection with a member which is adjustable longitudinally of the adjuster frame.

15 It is apparent that through the operation of the appropriate screw rod 12, through its crank handle 13, the nut and block on such rod will be moved lengthwise such operated rod. If the adjuster frame is in any but a

20 position in alignment with the cross heads, such movement of the blocks will cause a movement of the particular cross head, and through the rod 17, of the particular control lever 9. Therefore, any one or more of the 25 control levers 9 may be adjusted to control the speed ratio of the particular units as desired. The unit controls are, however, all mounted in one frame, and this frame is itself movable or of adjustable position, as

30 through its pivotal connection with the brackets. Therefore, all units may be simultaneously controlled through movement of the adjuster frame. This simultaneous control is proportional, in that it does not 35 vary the relative independent unit speeds, though these are capable of independent control in any operative position of the adjuster frame.

The parts are so preferably arranged that 40 when the adjuster frame is vertical on its pivotal supports, the cross heads will be in alignment with the frame and with each other. This is the position of zero delivery of the pumps, and of course operation of the

45 rods 12 will not affect the cross heads or levers 9, as the blocks 15 simply move freely lengthwise the cross heads.

In Fig. 6 there is shown a slight modification of the drive control, wherein an adjuster frame 18, is pivotally supported adjacent each control lever 9, and such frames 18, each carry a single adjusting rod 19, having its block 20 operating in the cross head 21, connected to the adjacent control lever 9, by a rod 22. In this form, the independent adjustment of the speeds of the units is obviously provided for, and the simultaneous adjustment is insured through the connection of all adjuster frames 18 by an operating rod 23. The possibilities of the control as thus arranged are fully equal to those of the preferred form.

If for any reason the resistance of the load machine of any unit should increase beyond the predetermined maximum operating

torque, a safety-valve 24 is provided for the motor of each unit, such valve serving to by-pass the motive fluid, and thereby avoid damage to the operating elements of the unit.

Having thus described the invention, what 70 is claimed as new, is:—

1. Means for controlling continuous rolling mills, comprising variable speed transmission units for each stand of rolls, a prime mover, and a system of control whereby the 75 speed ratio of each unit may be independently adjusted and the adjusted speeds may be simultaneously governed without altering the relative speed ratios.

2. Means for controlling continuous rolling mills, comprising a variable speed hydraulic transmission unit for each stand of rolls, a prime mover, means for regulating the speed of each unit at will, and means for simultaneously effecting proportional 85 speed changes in all the units.

3. Means for controlling continuous rolling mills, comprising a variable speed hydraulic transmission unit for each stand of rolls, means for selectively controlling said units, and means for simultaneously controlling them without disturbing the individual 90 adjustments.

4. Means for controlling continuous rolling mills, comprising the combination with 95 stands of rolls, of hydraulic transmission units, including a pump and a motor for each stand of rolls, a prime mover for operating the pumps, means for selectively governing the respective units, and means for operating the selective means for all the units as an entity without interfering with the relative adjustments of the same.

5. A control for a multiple unit continuous drive, comprising a unit control, and a 105 frame in which said controls are adjustably mounted, said frame being movable to simultaneously operate all unit controls.

6. A control for multiple unit continuous drive, comprising a pivoted frame, and a 110 control means for each unit independently and adjustably mounted in the frame.

7. A control for a multiple unit continuous drive, comprising a pivoted frame, an adjusting rod for the control of each unit 115 mounted in the frame, and means for operating the rods independently.

8. A control for a multiple unit continuous drive, comprising a control lever for each unit, a pivoted frame, and independent 120 means for operating each lever, said means being mounted in and movable with the frame.

9. A control for a multiple unit continuous drive, comprising a control lever for each unit, a pivoted frame, a threaded rod for each lever mounted for rotative movement in the frame, a cross head connected to each lever, and a connection between each cross head and the corresponding threaded 125

rod, whereby through operation of any rod the unit control lever is correspondingly operated and through movement of the frame all control levers are simultaneously operated.

10. A control for a continuous rolling mill drive involving a series of units including a pump and a motor, of a control lever for each pump, a frame pivoted for swinging

movement, a threaded rod for each control lever mounted in the rod for rotative movement, a nut having threaded connection with the rod, a block connected with the nut, and an open elongated cross head for each control lever in which the block of the corresponding threaded rod is slidably mounted.

In testimony whereof I affix my signature.

ALFRED CROOK.
